FINISHING WELT

Robert C. Schemmel, Union City, Ind.

Application November 10, 1931
Serial No. 574,159

2 Claims. (Cl. 155—184)

My invention relates to finishing welts and similar trimming strips of the type used in furniture and automobile body building to overlie and conceal the raw meeting edges of covering 5 fabric materials.

The invention contemplates an improvement in finishing welts of the blind nail type and has for an object the provision of such a welt with permanently secured interwoven wire means 10 functioning to maintain the hinged flap of the welt securely down in contact with the base thereof when the welt is applied in operative position.

A further object is to provide a welt of the 15 class indicated in which the wire is interwoven with a textile fabric formed of fibrous threads, the wire and fibrous threads combining to provide a skirt or flange capable of being easily and securely united to a bead filler or core by 20 means of an adhesive.

A further object is to provide a welt of the 25 class described in which the bead filler covering material comprises a woven fabric body having a pair of integrally united skirt portions of unequal widths which combine to receive a bead 30 filler, the wider skirt being folded around the filler and adhesively secured to the narrow skirt, which is itself directly secured by adhesive to the filler.

A further object is to provide a simple, inexpensive and compact assembly of materials 35 forming a blind nail finishing welt, including a pliable wire element disposed across the hinge line common to the base and flap portions of the welt, the wire being adapted to be folded down upon itself around a curve of extremely short radius as distinguished from the curves of longer radius used in the welts of the prior art.

Other and further important objects and advantages of the invention will be sufficiently apparent from the detailed description herein-after.

In the drawing which forms part of this 45 application for Letters Patent, and in which the same reference character designates the same part in the several views,

Figure 1 is a top plan view of a length of covering fabric showing the body and two skirt portions;

50 Fig. 2 is a cross sectional view taken on the line 2—2 of Fig. 1;

Fig. 3 is a cross sectional view on an enlarged scale of the fabric shown in Figs. 1 and 2, 55 illustrating the manner in which the bead fillers are associated therewith;

Fig. 4 is a similar cross sectional view of the part shown in Fig. 3 showing a further step in the process of assembling the parts;

Fig. 5 is a perspective view with one end in cross section of a completed welt applied to a 60 support;

Fig. 6 is a top plan view similar to Fig. 1, showing a modified form of covering fabric; and

Fig. 7 is a cross sectional view taken on the 65 line 7—7 of Fig. 6.

The welt includes a base portion adapted to receive nails, tacks or the like for fastening the same in position on a support, and a flap portion, including a bead filler, hinged to the base 70 portion and adapted to be lifted therefrom when the tacks are applied and driven home through the base, and subsequently to be folded down thereupon to cover and conceal the tacks.

Referring now to the drawing, the covering 75 material forming the base and enveloping the bead filler to form the flap comprises a strip of woven threads of cotton or the like disposed in the form of a main body portion 1, a relatively narrow skirt 2 and a relatively wide skirt 3. 80 The two skirts branch from the main body along a common line 4. A pliable wire element is woven into the narrow skirt 2 and the adjacent portion of the main body 1, thus extending 85 across the line 4 for a purpose hereinafter explained. The wire element is conveniently provided in the form of a continuous length of wire 5 which is folded back and forth upon itself across the line 4 and interwoven securely with 90 the fibrous threads of the skirt 2 and the adjacent portion of the main body 1.

A relatively large bead filler 6, preferably of half-cylindrical shape, is associated with the covering fabric to provide the bead flap of the welt. As shown in Fig. 3 the filler 6 is received between the two skirts of the covering fabric, with its under surface adhesively secured to the upper surface of the narrow, wire-containing skirt, while the wider skirt, devoid of wire, overlies the upper surface of the filler and has its free outer margin adhesively secured to the under surface of the narrow skirt 2. If desired, adhesive may be employed to secure the major portion of the skirt 3 to the upper surface of 105 the filler 6, but I have found that this additional adhesive is not required, since the bond between the skirt 2 and the filler, in combination with that uniting the skirt 2 and the outer margin of the skirt 3, is sufficient to unite the 110

entire assembly of both skirts and the filler with great security and permanency.

A distinctive advantage of the welt which forms the subject of this application for Letters 5 Patent resides in the novel association of fibrous threads and metallic wire woven together in the skirt 2, whereby the fibrous thread components and the skirt 2 adapt the skirt to be securely bonded by adhesive to the filler 6 in a 10 union which is far superior to any which has been heretofore attainable directly between a bead filler and wire not associated with fibrous threads. It will be appreciated of course that the interwoven condition of the wire and the 15 fibrous threads in the skirt 2 effectually prevents separation of the wire out of the skirt. The fibrous threads of the skirt 2 unite through the medium of an additional adhesive coating with the free outer margin of the skirt 3. The 20 assembly of both skirts and the interposed filler 6 is thus permanently and securely united.

The free outer edge of the main body portion 1 is folded back upon itself, conveniently 25 around a second and preferably smaller filler 7, to form a multi-ply base portion 8, through which nails, tacks or equivalent fastening means 9 are adapted to be passed for the purpose of securing the welt to a support 10. The assembly of filler 6 and skirts 2 and 3 provides a flap 35 11 which is hinged to the base 8 substantially along the line 4. In practice, the flap 11 is folded down into contact with the base 8 after the fastening elements 9 have been driven home therethrough, the wire material serving to maintain the flap and base in contacting relation.

It will be noted that welts constructed in the manner hereinabove described include a pliable wire ply made integral with the welt covering material and consequently not liable to separation therefrom.

In addition, the wire material incorporated in the welt to secure the flap and base in contacting relation is entirely concealed within the welt structure, being located wholly beneath the flap 45 11 when the welt is in applied condition.

Furthermore, since both of the folded plies of the wire material underlie the bead filler 6, the wire is folded down upon itself around a curve 50 12 of extremely short radius, thus differing from wire-ply-containing welts of the prior art wherein the wire ply is carried around the upper surface of the flap bead filler. It will be obvious that the fold in the wire of the present invention is adapted to approach the character of a 55 distinct crease and thus to a much superior degree serve to hold the flap tightly down upon the base.

It will be noted also that the integral, one-piece construction of the welt covering material 60 permits the assembly of the several elements of

the welt without the use of stitching. While a line of stitching may, if desired, be passed through the plural plies of the base, such stitching is not required, the adhesive coating used in the base and on the skirt surfaces being sufficient to bond the several parts of the welt together.

Practice of the modified form of the invention shown in Figs. 6 and 7 results in a slight economy of the fibrous thread used in the fabrication of the covering material, since this modification of the invention contemplates terminating the fibrous thread constituent of the skirt 2 short of the edge of the wire material of the skirt. It will be understood that the free outer margin of the wide skirt 3 is adhesively united to the fibrous thread portion of the narrow skirt 2 of Figs. 6 and 7, in exactly the same manner as shown in the disclosure of the preferred form of the invention.

It will be understood that the invention is shown in this application for Letters Patent in certain preferred forms of embodiment only, merely by way of exemplification. The invention is capable of embodiment in other and further modified forms, and all such modifications to the extent that they embody the principles of the invention as pointed out in the appended claims, are to be deemed within the scope and purview thereof.

I claim:

1. A finishing welt comprising a unitary strip of woven fabric having a main body and having a relatively wide skirt and a narrow skirt branching from the body along a common line 110 and integrally interwoven with the main body, a filler secured between said skirts to provide a flap, the main body of the strip being folded over on itself to provide a two-ply base, the flap being folded over on the base and being 115 hinged thereto along the line common to the main body and the two skirts, a layer of pliable wire being woven into the narrow skirt and a portion only of the main body adjacent said line.

2. A finishing welt having a two-ply base and a beaded flap hinged thereto, the base comprising a unitary strip of woven fabric folded upon itself, one of the two plies being divided at its free edge into two branching skirts each 125 integrally interwoven with said ply, one skirt being relatively wide and the other being narrow, a plurality of lengths of pliable wire being woven into the narrow skirt and a narrow adjacent portion of the base, said wires crossing the free edge of the base, and a filler secured between said skirts and adapted to hinge along the free edge of the base constituting the beaded flap.
